Primary Examiner—James M. Gandy*Attorney, Agent, or Firm*—Robert R. Reed; Russell W. Warnock[57] **CLAIM**

The ornamental design for a tire, as shown and described.

DESCRIPTION

FIG. 1 is a perspective view of a tire showing my new design, it being understood that the tread pattern is repeated throughout the circumference of the tire, the opposite side being substantially the same as that illustrated; and,

FIG. 2 is a front elevation view of the tire of FIG. 1 showing my new design.
